UNITED STATES PATENT OFFICE.

ALEXANDER AITCHISON BROWN, OF RUTHERGLEN, GLASGOW, SCOTLAND.

FOLDED BLANK BOX.

1,366,309.

Specification of Letters Patent.

Patented Jan. 18, 1921.

Application filed June 1, 1920. Serial No. 385,786.

To all whom it may concern:

Be it known that I, ALEXANDER AITCHISON BROWN, a subject of the King of Great Britain and Ireland, and residing at Luzern, 5 Buchanan Drive, Rutherglen, Glasgow, Scotland, have invented certain new and useful Improvements in and Relating to Folded Blank Boxes, of which the following is a specification.

10 This invention relates to folding, collapsible or knockdown boxes, more particularly those of cardboard as used for carrying and protecting incandescent gas mantles.

Such boxes are usually constructed from 15 a blank of cardboard divided into panels by creasing lines and cuts, the various panels being so bent and moved relatively to one another, that a square or rectangular box is produced having therewithin a curved shelf 20 (hereinafter referred to as a fixed shelf) under which may be accommodated two of the three projecting feet or ears of a mantle ring while the third is secured by a curved movable slide which is pushed in by hand 25 after the mantle has been placed in position. In this way, the mantle is securely held and protected from damage during transit.

It is found in practice that the movable slide, being loose, is apt to become mislaid 30 and lost or damaged, and one object of the present invention is to so arrange the blank that the slide forms an integral or definitely connected part of it.

Another object is a blank which shall not 35 involve any unnecessary waste of material when a number of them are being cut out, stamped or otherwise formed.

Another object is an improved construction in which the mantle is inserted at one 40 side of the box.

The invention principally consists in so forming the box blank that the action of completing the folding of the box automatically actuates the movable shelf or 45 shelves to insure the proper holding down of the mantle ring within the box.

The invention also consists in a box blank with which is integrally formed the movable shelf adapted to engage with one or more 50 lugs on the mantle ring, said shelf or member having wings or lever arms by which it is automatically operated by the final closing operation of the box.

Referring now to the accompanying drawings which illustrate various forms of the 55 improved box,

Figure 1 is a plan view of a blank, the single continuous lines representing cuts, while the chain dotted lines represent scoring or crease lines;

60

Fig. 2 is a plan view in perspective showing the nearly completed folding of a box from the blank shown in Fig. 1. The closing of the box shown in these two figures is effected by a flap turning up from the bottom 65 of the box.

Fig. 3 is respectively a plan view of a blank of a modified form.

Fig. 4 is a perspective view of the side closing box formed by the blank in Fig. 3.

70

Fig. 5 is a view of a modified form of blank.

Figs. 6 and 7 are plan views of two modified forms of blank.

Fig. 8 is a modification hereinafter described, and

Fig. 9 is a perspective view of a box which includes the modification shown in Fig. 8.

In carrying the invention into effect and referring to Figs. 1 and 2, the blank is longitudinally divided as by a cut line *a* and a crease line *b* into two halves *c* and *d* respectively. Each half is subdivided by crease lines *e* into five panels *c'* to *c⁵* and *d'* to *d⁵* respectively. The half *d* constitutes the top panel *d⁴*, the bottom panel *d²* and two of the sides *d¹* and *d³*, while the half *c* provides the four remaining sides *c¹* to *c⁴*. Each of the narrow end portions *d⁵* and *c⁵* forms a securing flap. At one side of the part *d* there is attached for a part of its length by a crease line *f*, a strip *g*, hereinafter called a shelf strip, which is transversely divided by creasing and cutting into three panels *g¹*, *g²* and *g³*. The center panel *g²* is cut away as shown so that it may afterward form a fixed shelf *h* to accommodate a lug or lugs on the mantle ring. The corners of the panel *g²* are cut as shown at *k* 100 to space the shelf a convenient distance to allow the lugs to pass underneath.

At the side of the part *c* there is attached by a crease line *l* an extension piece *m* which will afterward form the movable shelf to co-operate as will be described with the fixed shelf member *h* to hold down the mantle ring, and such extension piece is fitted with wings or lever portions *n* by which it may be actuated.

In setting up the box the fixed shelf strip *g* is turned up on edge and the two free

110

panels g^2 and g^3 thereof bent around to form with the remaining panel g^1 , three sides of a square upstanding on the half d and fitting around the panel d^1 . The other part c is 5 now turned up on edge and is swung around so that its panels c^2 , c^3 and c^4 fit around the upstanding shelf strip g forming a square box with one side open the bottom of which is formed by the panel d^1 . The flap c^5 is then 10 tucked in between the panel c^1 and the panel g^3 of the shelf strip. The box is now upended on to the bottom panel d^2 (forming with c^2 a double bottom) into position somewhat as illustrated in Fig. 2 with the extension piece m forming the movable shelf extending flat from the bottom of the open side. The mantle with its ring is now placed 15 in the box with one or two of its lugs beneath the fixed shelf h , and the extension m forming the movable shelf is then turned up on edge which action will cause the two side wings n to bend inward toward each other and leaving their sharp corners projecting so that when the panel d^3 is swung up to 20 close the open side, it engages with the wings n and presses them in at the same time turning down the movable shelf upon the remaining lug or lugs of the mantle ring. The folding of the box is finished by folding 25 down the top panel d^4 upon the panel c^4 , and the box finally completed by tucking the flap d^5 in behind the panel d^1 .

In a second modification as shown in Figs. 3 and 4, the blank is so formed that the 30 usual fixed shelf is replaced by a movable automatically actuated shelf similar to that above described, so that both shelves are thus automatically adjusted.

In such a construction the blank comprises 35 a longitudinal center part o transversely divided by crease lines into five panels o^1 to o^5 . One side of the panel o^4 of part o is provided with a panel p , a crease line dividing the two and adjacent the panel p and separated 40 by a cut line is a shelf member q , attached by crease lines to panel o^3 . The shelf member is shaped as shown and carries a wing or lever r on one side. On its other side the center part o carries by a creased line, 45 two panels s and s^1 respectively positioned adjacent the main panels o^2 and o^1 while a corresponding shelf member t fitted with a wing t^1 is attached by a double crease line to the other side of panel o^3 and separated 50 by a cut line from panel s . In setting up the box, the sides o^2 and o^4 are turned up relatively to the bottom panel o^3 , and the top o^1 is bent over to form a four sided square. The shelf q is then turned up on 55 edge and is finally adjusted into position by closing in the side panel p , the flap p^1 being finally tucked in. The panel s^1 which now 60 extends from the top is turned down into the open side and then upward as shown in 65 Fig. 4 against the top panel o^1 to reinforce

it from inside and in doing so, secures the flap o^5 on the side panel o^4 , after which the shelf t is inserted and finally adjusted in position by the closing in of the side panel s and secured by tucking in the flap s^2 . For 70 the purpose of affording a stop adapted to fit against the side face of one of the mantle ring lugs, the shelf t is provided with an ear piece t^2 attached by a crease line as shown in Fig. 3. The side t^3 forms an abrupt 75 shoulder which engages with one side of one of the lugs on the mantle ring.

It is to be noted that if desired the ear piece t^2 and the reinforcing panel s^1 may 80 both be omitted or only one of them.

The modified form of blank shown in Fig. 5 is generally similar to that in Fig. 1, the order of the panels being, however, somewhat different. One longitudinal half u of the blank is transversely divided by creasing, 85 into a top panel u^1 , side panel u^2 , bottom panel u^3 , side panel u^4 and flap u^5 while the other half v is similarly divided into a half top panel v^1 , side panel v^2 , bottom panel v^3 , side panel v^4 and half top panel v^5 . The 90 shelf strip w and the extension x is similar to those in Fig. 1, but the former carries a tongue w^1 adapted to engage a slotted opening w^2 on the crease line between panels v^1 and v^2 . To construct the box the shelf strip 95 w is turned up on edge and the two free panels thereof swing around as described in connection with Fig. 1, after which the half v is turned up and the panels are fitted 100 around the shelf strip, the tongue w^1 being passed through the opening w^2 . The box is now upended on to the bottom panel u^3 and the top panel u^1 closed over the half panels v^1 and v^5 , and secured by adhesive or wire stitching so that both the top and the bottom are double. The extension x is then 105 turned into the opened side and finally adjusted by turning up the panel v^4 the flap u^5 being tucked in and completing the box.

Referring to Fig. 6 the main part y of the 110 blank is transversely creased to form the top panel y^1 , side panel y^2 and y^4 , bottom panel y^3 and flap y^5 . On each side of the panel y^4 panels z and z^1 are provided by creasing. These panels z and z^1 carry flaps z^2 and z^3 115 respectively, while on each side of panel y^3 are fitted the shelf extensions 2 and 2^1 fitted with wings 3 and 3^1 .

The box is set up by turning up the panels 120 y^4 z and z^1 on edge about the crease which separates the panels y^3 and y^4 and folding around the remaining panels y^1 and y^2 to form a four sided figure, the parts y^1 and y^5 being secured by adhesive or stitching. The shelf 2^1 is then turned in and the side panel 125 z^1 , which forms the back of the box, is then turned in and thus adjusting the shelf by the wing 3^1 , the flap z^3 finally being tucked in. To complete the box the shelf 2 is turned in and the closing of the front panel z actu- 130

ates the wing 3, and the closing in of the flap ε^2 completes the box.

The modified blank in Fig. 7 comprises a main part 4 divided by crease lines so as to form a top panel 4^a, side panels 4^b and 4^d, bottom panel 4^c and a flap 4^e. The panels 4^b and 4^d are attached by crease lines, the remaining side panels forming respectively the back 5 having a flap 5^a, and the front 6 having a flap 6^a. The shelf extensions 7 and 8 each having an actuating wing 7^a and 8^a are attached to the bottom panel 4^c and in order that the shelf 8 may have the necessary space beneath it, the corner 8^b thereof is extended beyond the creased line 8^c. When setting up the box, the side panels 4^b and 4^d are turned up on either side of the bottom panel 4^c and the panel 4^a is bent over to form the top and is attached to the flap 4^e by adhesive, wire stitching or otherwise. The shelf 8 is turned in and the back is closed in by the panel 5 and secured by the flap 5^a. The other shelf 7 is actuated and the front closed in by panel 6 and finished by tucking in the flap 6^a.

From the various arrangements above described it will be seen that the form and arrangement of the blanks may vary considerably and that the co-acting shelf members may form part of one or more panels. Such panels while preferably being integral with the other panels of the blank may nevertheless be formed as a separate unit member carrying one or both shelves and afterward attached to a desired main panel by any suitable means, such as adhesive, riveting, wire stitching or the like. One example of such a construction is shown in Fig. 8, in which both shelf members 9 with double wings 10 are attached by double crease lines 11 to a panel 12 which is subsequently secured to any suitable main panel of a blank, and thus serve as a reinforcement to the bottom of the box. It will be obvious also that the unit illustrated in this figure may be applied to either a knockdown box or a collapsible box and a perspective view of the latter box is illustrated in Fig. 9 in which the unitary shelf member in Fig. 8 is mounted as shown, the box being closed by back and front side panels 13.

In the various other modifications, the panel to which one or both movable shelf members are secured, may vary in its position in relation to the other panels, and thus may alter the general form of the blank, but this will not affect the basic idea of the present invention which consists in the automatic actuation of one or both shelves. The width of the shelf members is also an important consideration and in most of the modifications it is approximately half the width of the main panels. A saving of material is effected and the two shelf members when turned come edge to edge, but in the

modifications shown in Figs. 3 and 7, the shelves are such that they overlap. It is to be noted that each shelf may have one or two actuating wings, and if the former construction is adopted the wing on one may be on the same side as the wing on the other or they may be on relatively opposite sides.

One important consideration in deciding the form of blank is to economize material and the arrangements illustrated are such that most of them permit, especially by the half width of the shelves, a reversing of the adjacent blanks when first cutting them out, so that they fit into one another to effect maximum saving of material.

Referring to Figs. 1 and 5 it is to be noted that the shelf strip in fitting against the bottom and two sides provides a stiffening corner member that is not fastened as by wire stitching, for instance if fastening is desirable the tongue w^1 Fig. 5 may be employed.

Having now described my invention, what I claim as new and desire to secure by Letters Patent is:—

1. A folding collapsible box having a shelf with an edge shaped to engage an article and provided with a wing having an edge extending into a position to be engaged by one of the panels of the box, said wing exerting pressure on the shelf toward one of the box panels when its edge is engaged by one of the panels, said shelf cooperating with the second mentioned panel for gripping an article between them.

2. As a new article of manufacture, a box blank including a panel, one side of which carries a shelf extension designed to be automatically folded over on to the panel for the purpose described, a second panel integral with the blank, and a wing connected to the shelf extension and having an edge engaged by a second panel for forcing the shelf extension toward the first panel.

3. A new article of manufacture comprising in combination a box blank, divided into panels for forming the top, bottom and sides of a knockdown or collapsible box, the bottom panel being provided with a shelf extension, and means on said extension for automatically turning the same over upon the bottom panel by positioning one of the sides when setting up the box.

4. A new article of manufacture comprising a box blank, a shelf strip attached thereto at one side for a part of its length, a shelf extension on the other side of the blank and means on the said extension to automatically bring it into co-acting position with the said shelf strip when setting up the box.

5. A knockdown box as claimed in claim 4, which is reinforced at two of the corners and the bottom by a shelf strip.

6. A knockdown box as claimed in claim 130

4, in which the shelf strip is provided with a tongue at one end thereof which engages an opening in one of the side panels of the blank to assist in securing the parts together.

7. A knockdown collapsible or folding box of the kind defined by claim 4, in which the shelf extension carries a stop which is adapted to be positioned against the side of one of the mantle ring lugs.

8. A collapsible knockdown or folding box including a blank provided with a number of panels, a shelf panel having an integral shelf strip which is folded and spaced from one of the panels to provide for engaging a mantle ring, a shelf extension integral with one of said panels and folded into alinement with said strip to provide a

locking means for securing the ring, and means connected to the shelf extension and engageable with one of the box panels for forcing the shelf extension toward the shelf panel.

9. A knockdown box formed of sheet material and including top, bottom, and side panels, combined with a mantle holding shelf including a plurality of oppositely disposed alined jaws, each of said jaws being integral with a panel of the box, each jaw being folded inwardly upon a panel, and one jaw being provided with means engageable with one of the box panels for forcing said jaw toward one of the panels.

In testimony whereof I have signed my name to this specification.

ALEXANDER AITCHISON BROWN.
